(57) CLAIM

The ornamental design for a price marker, as shown and described.

DESCRIPTION

FIG. 1 is a front view of a price marker;

FIG. 2 is a back view thereof;

FIG. 3 is a top view thereof;

FIG. 4 is a bottom view thereof;

FIG. 5 is a side view thereof;

FIG. 6 is a side view opposite to the side view of FIG. 5;

FIG. 7 is a top and front perspective view thereof; and,

FIG. 8 is a bottom and back perspective view thereof.

The broken lines in the drawings are shown for the purpose of illustrating environmental structure and form no part of the claimed design.
